UNITED STATES PATENT OFFICE.

ADDISON G. WATERHOUSE, OF NEW YORK, N. Y., ASSIGNOR TO THEODORE F. BOURNE,
TRUSTEE, OF MONTCLAIR, NEW JERSEY.

METHOD OF DISTILLING.

991,570.

Specification of Letters Patent.

Patented May 9, 1911.

Application filed March 13, 1909. Serial No. 483,334.

To all whom it may concern:

Be it known that I, ADDISON G. WATERHOUSE, a citizen of the United States, and resident of New York city, borough of the Bronx, in the county of New York and State of New York, have invented certain new and useful Improvements in Methods of Distilling, of which the following is a specification.

- 10 In my application Serial No. 449,995 filed August 24, 1908, now Patent No. 939,361, Nov. 9, 1909, I have set forth a method of distilling wherein a body of liquid is heated, the temperature of the liquid being maintained at approximately the temperature required for vaporizing the desired properties from the liquid, and the flow of the liquid controlled by the temperature in the still or of such liquid, and wherein also the fresh inflowing liquid is heated by the heated outflowing exhaust liquid; and in said application I have also set forth the method of regulating the heat applied to the still by the products of such distillation.
- 15 25 My present invention has for its object to further improve the method of distillation and rectification of volatile products, such as alcohol, at one operation and in an automatic and continuous manner.
- 20 30 By this invention I am enabled to effect the separation of the desired vapor, such as of alcohol, from worts without bringing such vapor and worts into condensing relation to each other, and also to generate the maximum amount of desired vapor from the worts while limiting the generation of aqueous vapor to a minimum.

In order to describe my invention that those versed in the art may carry out the same, reference will be had to the accompanying drawings, in which like characters indicate like parts, and in which—

Figure 1 is a sectional elevation of an apparatus adapted to carry out my invention; Fig. 1^a is an enlarged sectional view of the boiler; Fig. 2 is a horizontal section of the apparatus substantially on the line 2, 2, in Fig. 1; Fig. 3 is a central section of Fig. 2; Figs. 4 and 5 are details of a modification.

Fig. 1 shows diagrammatically and partly in section a suitable apparatus comprising

a supply pipe A, a heat exchange B, a heater or evaporator C, a boiler or receptacle D, a condenser E, and analyzing or condensing columns F and G.

The heat exchange B, which may be of any suitable form, is shown as a closed vessel having two separate compartments formed by partitions adapted for transferring heat by conduction from one compartment to the other, into one of which compartments the supply of fresh liquid, such as fermented worts, enters at its lower extreme through pipe A, and then through a stuffing box and nipple B', into a lower chamber B², whence it ascends through a number of parallel tubes B³, into an upper chamber B⁴, whence it continues through a valve B⁵, which normally remains closed by the tension of spring B⁶ until opened subject to certain conditions to be hereafter described.

The conditions under which the valve B⁵ is opened are, among other things, such as to permit of the flow of liquid through the heat exchange as stated, and also such as to cause a corresponding volume of hot exhausted liquid or worts to flow from the boiler through pipe D⁵, and enter the upper part of the outer shell of the heat exchange B, outside of tubes B³, whence it will slowly descend until it is finally discharged from the shell at its lower extreme, and out through the discharge pipe B⁹. In this way the outflowing hot and exhausted liquid which descends within the shell of heat exchange B and outside of tubes B³, transfers its heat, by conduction, to the cold fresh liquid which is at the same time ascending tubes B³, so that by the time the hot liquid descends from the top to the bottom of the heat exchange it will be discharged in a relatively cold state, while the relatively cold inflowing liquid which enters the bottom of the heat exchange will become hot or heated by the time it has ascended to the top thereof, thereby causing the heat transferred to the inflowing liquid to be returned to the apparatus and used over and over again. The thus heated fresh liquid after being allowed to pass the valve B⁵, ascends through pipe B⁴, into a chamber C' shown in annular form, which

comprises part of evaporator C. This evaporator is shown partly in section in Fig. 2, and is provided with a central floor C³, an outer cylindrical shell or wall C⁴, and an inner concentric wall C⁵, which walls are connected by a radial partition C⁶. The bottom of floor C³ of the annular chamber C', is provided with a series of heating tubes or passages C⁷, C⁸ extending into boiler D, through which tubes liquid can flow successively, as by flowing into and then out of one tube, and then into and through the next tube; and so on until the liquid has entered and flowed from each tube without escaping from chamber C'. The liquid, as stated, enters chamber C', through the pipe B⁹, and then flows around through the chamber C', but in so doing enters and flows from each of the heating tubes or passages C⁷, until the liquid is discharged into boiler D through an open-bottomed pipe C⁸, placed at the farther extreme of the chamber C', beyond the inlet pipe B⁹.

25 An inner wall C¹⁰ is shown formed by the floor C³ and concentric wall C⁵. In wall C⁵ an opening C¹¹ is shown, which allows liquid, as it enters through the pipe B⁹, to flow from any determined part of the chamber C', into the well C¹⁰, and also allows the same liquid, or more liquid which may accumulate in the well as the result of condensation, to flow back from the well into chamber C', whence it will follow the course of the liquid on its way around chamber C', as described, until it is discharged through the open part of pipe C⁸. The lower ends of tubes C⁷ are closed, their upper open ends communicating with chamber C'.

40 Inside of each heating tube C⁷ is a circulating pipe C¹², which is open at both ends, its purpose being to assist the circulation of liquid through tubes C⁷ by offering a passage for the cooler liquid to descend within pipe C¹² from chamber C', and take the place of other liquid as it tends to rise in the outer tube C⁷ after being brought to a higher temperature by the heat transmitted to it within boiler D through the tube C⁷.

45 Other means may be employed for causing such circulation of liquid, such as by forming a continuous passage by a series of pipes connected by return bends, or as represented in Fig. 4, which shows two tubes C⁷, C⁷, closed at their lower ends, and extending down from under the chamber or runway C', each tube being provided with diametrical partitions C¹³, as shown, so that the course of the liquid as indicated by the arrows in Fig. 4, will be down and under each partition, and then up the other side and so on in its way through each succeeding tube C⁷.

50 Fig. 5 shows a plan of part of Fig. 4, 60 showing the open top of one of the tubes C⁷,

with its partition C¹² corrugated longitudinally, so as to give it a spring tension which will adapt it for fitting the interior of the tube and make it easy to insert or draw out for the purpose of cleaning the parts.

The evaporator C, being connected to the boiler, as by flange C², provides a closed boiler, so that whatever steam or vapor is generated in the boiler, in order to escape, must pass out through the side pipe E⁴, and then up into the condensing column E, as hereinafter described. The evaporator C is also covered and made a closed vessel by means of the plate C¹⁴, which is bolted to flange C¹⁵, so that all the vapor generated from the liquid flowing through the evaporator C is compelled to pass up through opening C¹⁶, in the plate C¹⁴, and then into the analyzer or condensing column F, that communicates with opening C¹⁶, the further action of which vapor will be explained.

The liquid discharged into the boiler D from or through the vaporizer or evaporator C would soon fill or overflow the former, and to prevent this and maintain a predetermined liquid level in the boiler a float D' is provided, which will be supported on the surface of the liquid and rise and fall with it, as the surface of the liquid changes from any predetermined level, such as represented by the dotted line W. To this end float D' is shown connected by rod D², to a pivoted lever D³, which opens or closes discharge valve D⁴, controlling the passage through pipe D⁵, serving to keep the liquid at the level required.

Heat may be applied to boiler D in any way known to the art, but which in the present case is represented by the gas burner H. This heat applies to the liquid which has been discharged into boiler D, and such heat is conducted to the fresh liquid while it is passing through evaporator C, and circulating in the tubes C⁷. One of the leading objects of this invention is to limit the temperature to which the liquid in boiler D can be raised, so that such temperature will not exceed that which is just sufficient for driving substantially all of the alcoholic or desired vapor from the worts or other liquid without generating any more steam or aqueous or other vapor from it than is possible. Such temperature for alcoholic distillation is slightly below the boiling point of water, at about 210° Far. To effect this a thermal regulator is used and adjusted for operating the admission valve B⁶, so that at approximately the temperature desired fresh liquid will be allowed to flow through valve B⁶, pipe B⁹, and evaporator C, into boiler D, as fast as, but no faster than, the applied heat can maintain the temperature which effects this flow. To accomplish this a thermostat or heat-actuated regulator is shown, submerged in or placed in thermal commun-

nication with the liquid in the boiler, the temperature of which is to be limited. The regulator shown comprises a tube or feeler D⁸, closed at its free end and in open communication with a recess D⁶, closed by a flexible diaphragm or movable member D⁷ adapted to be actuated by a pressure created by the heat of the liquid in the boiler acting upon some volatile fluid confined within 10 feeler D⁸, and recess D⁶, whereby a determined temperature of the liquid in the boiler will produce motion of the diaphragm D⁷, which is transmitted to valve B⁵, through valve stem B⁷, in a way which will 15 overcome the resistance of its spring B⁸, and open valve B⁵, to an extent which will permit the flow of fresh liquid in the boiler as fast as the applied heat can maintain its 20 temperature at approximately the point stated and no faster. In other words, when the temperature of the liquid being treated rises so as to create an initial pressure in the feeler D⁸ such pressure will cause the valve B⁵ to open to a limited extent, and a 25 further rise of temperature of such liquid will create a greater pressure in the feeler to cause the valve to open more, and so on during the rise in temperature, but as cooler liquid enters the boiler and thereby tends 30 to reduce the temperature of the liquid controlling the feeler D⁸ the pressure in the feeler decreases proportionately, the result being that there will be a continuous flow of fluid through the still which is not necessarily constant in volume, but variable according to the pressure caused in the feeler by the temperature of such flowing liquid, and according as such temperature may 35 vary, whereby the temperature of the current of liquid flowing through the still is prevented from rising too high and likewise prevented from dropping too low, the flow of the current of liquid being proportionate to the amount of opening of valve B⁵ which 40 depends at all moments upon the temperature of the liquid creating pressure of fluid in the feeler.

Heretofore, in distilling alcohol in a continuous manner, the richer or fresh worts or 45 solutions fed into the still have been weakened or diluted by being fed into the exhausted liquid so that a much higher temperature is required to separate the alcohol in its weakened state, from such diluted 50 liquid, than would have been required at first or before it had been so diluted, and this higher temperature results in generating a larger percentage of steam or aqueous vapors, as well as those of fusel oils, which are 55 objectionable and should be avoided. Again, in allowing alcoholic vapor which has been generated to come into contact with liquid that is cooler than the vapor, much of such vapor is condensed by contact with such 60 liquid and carried back to the diluted solu-

tion, from which it must be redistilled in a way which entails a greater use of heat and encumbers the still with an increased percentage of objectionable vapors which are difficult to separate from those desired.

The foregoing objections become apparent when it is observed that the temperature required for driving alcoholic vapor from an aqueous solution varies, as, for example, with a solution of 90 per cent. of alcohol, its vapor 70 will start at about 171° Far., in a 25 per cent. solution its vapor will start at about 187° Far., and from one per cent. solution the alcoholic vapor will start at about 210°, and its evolution be completed before the boiling 75 point of water is reached.

By my invention the above objections are to a great extent avoided, by means of progressive increments of heat applied to the solution as it becomes weakened in alcoholic 80 properties (which increments of heat result from the period of time it takes the liquid to pass through the apparatus), so that the alcoholic vapor will be generated progressively at the minimum temperature under which it 85 can be driven from the continually weakening solution, and conducted from the solution and condensed, so that the alcoholic vapor will not return to and be condensed by contact with liquid which is cooler than the 90 liquid from which said vapor was driven. These results are effected as follows: As the 95 fresh liquid rises through the heat exchange B the heat from the hot liquid being discharged in thermal communication with such fresh inflowing liquid causes the formation of alcoholic vapor from such fresh liquid, which vapor with its liquid continues up through the heat exchange and then 100 through valve B⁵, and pipe B⁶, into the 105 evaporator C, where the vapor passes over the surface of the liquid circulating around the chamber C', (which liquid is continually rising in temperature) until such vapor passes up into the analyzer or condenser F, 110 then as the liquid flows around the evaporator and circulates in each of the tubes as described, the liquid in the tubes C' absorbs heat both from the steam and vapor generated in the boiler, and which is above the 115 liquid therein, as well as the heat which is directly applied to the liquid in the boiler, thus continually increasing the heat of the advancing liquid as the alcohol which it contains grows less in percentage, so that the 120 vaporization of the alcohol takes place at the lowest practicable temperature. Now, the 125 alcoholic vapor which these increments of temperature create, will not flow backward to the cooler and succeeding liquid which would cause its condensation, because the first vapor generated is flowing from that direction, so that it with succeeding vapor crowds onward over the surface of liquid which is constantly growing hotter, until all 130

the vapor from the liquid is forced up through the opening C^{16} , in plate C^{16} , and then upward through the analyzer column or condenser F.

5 When the exhausted liquid from which most of the alcohol has been extracted during its passage through the evaporator C is discharged into the boiler D, as described, it is therein raised to the limit of temperature 10 to be imparted to such liquid, which increase of temperature drives substantially all of the remaining alcoholic vapor from such liquid, and with such vapor more or less aqueous and fusel oil vapors are or may 15 be carried, which latter are mostly condensed after passing through the side pipe E^4 into column E, while the alcoholic vapor continues on through connecting pipe E' into the top of the analyzing column or condenser F.

The condensates, which are mostly water, and which form in the condensing column E, and in the analyzing column F and in column G, are disposed of as follows: The 25 drain tube E^2 leads that condensate which forms in column E back to evaporator C, while that which forms in column F returns to evaporator C by gravitation, and that which forms in analyzing column G, returns 30 to evaporator C through the drain tube G^2 .

The columns adapted for arresting aqueous vapors and allowing the alcoholic vapors to continue to a final condenser, to be connected with pipe G^2 , (which are not 35 necessary to be shown) are herein represented as cylinders E, F and G, which may be of any desired length, or increased in number, and joined in series as the columns F and G are joined by means of the connecting pipe G' . Such columns may be formed in any way known to the art and used for performing the condensing, analyzing or rectifying work of a still, but in this case 40 preference is given to plain cylindrical columns, provided with brushes or string-like hangings, as shown at E^3 and F' , which may be composed of any unchangeable material, and formed as chains, strips or pendant fibrous material, adapted for finally dividing 45 and comminuting the vapor, and causing it to flow in a constantly deflected, sinuous and irregular course through the columns; and also offering ample surfaces upon which the aqueous vapor can condense 50 and find conductors or passages down which the condensate can gravitate or return to its source.

A gas burner H may be placed under boiler D, and this burner may be supplied with gas 60 from any permanent source through the gas pipe H' , but so that it will only supply a limited amount of gas, or just sufficient for operating the still slowly, and not under any conditions to rush it beyond its minimum 65 capacity. An auxiliary fuel pipe H^2 leads

to the burner H from the analyzer column G or other suitable part of the still, and supplies fuel either in the form of vapor or a condensate from the still, so that the fuel furnished through pipe H^2 will cause more 70 or less heat to be produced from the burner H, and this more or less heat will be such as to rush or retard the working of the still in ways which will automatically govern its action to that which will be to its best working advantage.

With the arrangement shown if the vapor or condensate from pipe H^2 should cause the heat to be too great at burner H the still would be rushed, causing an increase of 80 steam production which passing over and flowing from the pipe H^2 would cause modification or reduction of the flame produced by alcoholic vapor or condensate through pipe H^2 , whereby the still would be slowed 85 down to approximately the heat generated by the gas flowing from pipe H' , and so on. Such heating method is not claimed in this application as the same is included in my said application Serial No. 449,955 now 90 Patent No. 939,361, Nov. 9, 1909.

Having now described my invention what I claim is:

1. The method of distilling consisting in feeding liquid through a heated channel in 95 a still, and gradually increasing the temperature of such liquid as it advances through said channel to cause such liquid to finally reach a substantially predetermined temperature, causing vapor rising 100 from such liquid in said channel to flow over liquid hotter than that from which such vapor was derived, utilizing the heat of the residual portion of such liquid from which the desired parts have been evaporated in creating pressure of fluid, and causing pressure of such fluid to control the flow 105 of said liquid through the still.

2. The method of continuous distilling 110 consisting in feeding a current of liquid through a heated channel in a still, and gradually increasing the temperature of such current of liquid as it advances through said channel to cause such liquid to finally reach a substantially predetermined temperature, causing vapor rising from such liquid in said channel to flow over liquid hotter than that from which such vapor was derived, utilizing the heat of the residual 115 portion of such liquid from which the desired parts have been evaporated in creating pressure of fluid, and causing pressure of such fluid to effect the continuous flow and regulate the volume of the current of liquid flowing through the still.

3. The method of distilling consisting in heating a current of liquid to successively increasing temperatures, evaporating desired parts therefrom, and causing the vapor evolved from one portion of such liquid to 130

flow over the surface of such liquid that is hotter than said portion from which such vapor was evolved.

4. The method of distilling consisting in feeding a current of liquid through a still and gradually increasing the temperature of such liquid as it advances through the still until such liquid reaches a substantially predetermined degree, advancing cooler vapor which rises from such gradually heated advancing liquid in the direction of flow of such current of liquid and commingling such cooler vapor with hotter vapor from such liquid, and causing the heat of the liquid from which such vapor has been evaporated to discharge the residual liquid when it reaches such substantially predetermined temperature.

5. The method of distilling consisting in passing a current of fresh inflowing liquid into a still in juxtaposition to heated discharge liquid to heat the inflowing liquid, gradually increasing the temperature of such preheated current of liquid flowing through the still, and conducting the vapor rising from said current of liquid in the direction of flow of the liquid and over the surface of liquid that is hotter than that from which such vapor was evolved.

30 6. The method of distilling consisting in passing a current of fresh inflowing liquid into a still in juxtaposition to heated discharge liquid to heat the inflowing liquid, gradually increasing the temperature of such preheated current of liquid flowing through the still, conducting the vapor rising from said current of liquid in the direction of flow of the liquid and over the surface of liquid that is hotter than that from 40 which such vapor was evolved, and causing the heat of the part of the liquid from which the desired vapor has been extracted to control the flow of such liquid.

7. The method of distilling consisting in passing fresh liquid through and out of commingling contact with a body of heated liquid, discharging vapor at different points in its course through said body of liquid as generated from such fresh liquid, passing 50 such vapor over the surface of the liquid from which said vapor has been generated, and discharging such flowing liquid from which the desired properties have been evaporated into said body of liquid.

55 8. The method of distilling consisting in passing fresh liquid through and out of commingling contact with a body of heated liquid, discharging vapor as generated from such fresh liquid during the time of its 60 passage through said body of liquid, dis-

charging such flowing liquid from which desired properties have been evaporated into said body of liquid, and causing the flow of such fresh liquid to and the discharge of said body of liquid from the still by temperature utilized in such distillation.

9. The method of distilling consisting in passing fresh liquid through a heated passage having discharge openings between its ends, causing desired vapor from such liquid to be discharged from such openings during its flow through such passage, conducting such vapor over the surface of hotter liquid to mingle with hotter vapor from such liquid, and condensing such commingled vapors.

10. The method of distilling consisting in vaporizing desired parts from a liquid being distilled which are more volatile than the liquid from which they are derived by gradually increasing the temperature of such liquid, conducting the vapor so evolved over the surface of liquid hotter than that from which such vapor was derived to mingle with the vapor from such hotter liquid, and condensing such commingled vapors.

11. The method of distilling consisting in vaporizing desired parts from a liquid being distilled which are more volatile than the liquid from which they are derived by gradually increasing the temperature of such liquid, conducting the vapor so evolved over the surface of liquid hotter than that from which such vapor was derived to mingle with the vapor from such hotter liquid, condensing such commingled vapors, and causing the heat of such liquid from which said vapor has been evolved to control the flow of said liquid.

12. The method of distilling consisting in passing fresh liquid through and out of commingling relation to a body of liquid, discharging the fresh liquid into said body of liquid, applying heat to said body of liquid to cause evaporation of desired vapor from said fresh liquid and evolve vapor from said body of liquid, separately conducting the vapor from said body of liquid and from said fresh liquid to a condenser, condensing said vapors, and controlling the flow of the liquid by heat that effects the vaporization of the liquid.

Signed at New York city, in the county of New York, and State of New York, this 12th day of March, A. D. 1909.
